UNITED STATES PATENT OFFICE.

ALICE A. AZEEZ, OF NEW YORK, N. Y.

DESIGN FOR FABRIC.

SPECIFICATION forming part of Design No. 29,351, dated September 13, 1898.

Application filed August 3, 1898. Serial No. 687,642. Term of patent 3½ years.

To all whom it may concern:

Be it known that I, ALICE ATHEENA AZEEZ, a citizen of the United States, residing at New York, borough of Brooklyn, in the county of 5 Kings and State of New York, have invented and produced a new and original Design for a Fabric, of which the following is a full, clear, and exact description.

The drawing is a plan view of a fabric embodying my design.

The leading feature of my design consists of a fabric having a raised elongated figure rounded at its lower end and converging toward its upper end and having a ribbed surface.

Referring particularly to the drawing, 1

designates the base of the fabric, and 2 indicates an elongated figure in raised work thereon, the said figure being rounded at its lower end 3 and having its sides converging to a ragged upper end 4. The figure is formed with a number of longitudinally-disposed ribs or corrugations, and the upper portion of the figure is of darker shade than the lower portion. 20

I claim—

The design for a fabric herein shown and described.

ALICE A. AZEEZ.
